UNITED STATES PATENT OFFICE.

GILBERT H. SPECKMAN, OF AURORA, INDIANA.

WRENCH.

Application filed February 16, 1927. Serial No. 168,635.

My present invention pertains to wrenches, and has for its object the provision of a peculiar and advantageous wrench for holding and turning nuts and washers incident to the 5 installation of transmission bands in Ford automobiles.

To the attainment of the foregoing, the invention consists in the improvement as hereinafter described and definitely claimed.

10 In the accompanying drawing, forming part of this specification:—

Figure 1 is an elevation, partly broken away, illustrating the preferred embodiment of my invention.

15 Figure 2 is an elevation of the wrench taken at right angles to Figure 1.

Figure 3 is an enlarged detail longitudinal section illustrating the portions of my novel wrench provided for the reception and retention of a nut and washer complementary to the nut.

20 Similar numerals of reference designate corresponding parts in all of the views of the drawing.

25 Among other elements, my novel wrench comprises a handle portion 1 characterized by a longitudinal slot 2 and also characterized by an intermediate offset portion 3 in which is a longitudinally disposed aperture

30 4. At one end, the handle portion 1 is preferably, though not necessarily, provided with a circular enlargement 5 formed by parallel portions in which are transverse circular apertures and journaled in the said circular

35 apertures of the portions 5 are the trunnion portions of an annulus 6 which is provided with an opening 7 of angular form and is also provided with peripheral teeth 8, the latter for cooperation with a spring pressed

40 pawl 9 mounted in the handle.

As will be readily appreciated, the equipment described permits of the handle portion 1 being used after the manner of a ratchet wrench.

45 The handle portion 1 is provided at its opposite end, with reference to the ratchet mechanism described, with an annular portion 10 having an inwardly directed flange 11.

50 Mounted to turn about its axis in the annular portion 10 is the nut holding and turning member 12 of my improvement. The said member 12 is provided with a flange 13 opposed to the flange 11 of the annulus 10, and is also provided with an interior 14

shaped to receive a nut designated by 15, and is further provided with an interior rabbit 16 designed to receive the washer 17 complementary to the said nut 15. Externally, the member 12 is knurled as designated 60 by 18 to facilitate its turning by the thumb and finger of the operative, and it will be noticed that the knurled portion 18 extends laterally relative to the plane of the handle portion 1 so that the member 12 may be actuated with facility. It will also be noted by comparison of Figures 2 and 3 that the member 12 is provided with a circumferential flange 19, and that a split ring 20 is interposed between said flange 19 and the 70 flange 11 of the annulus 10, the split ring serving to hold the annulus 12 in proper working relation to the annulus 10 and this without interfering in any measure with the turning of the annulus or member 12 about 75 its axis in the annulus 10. It will be also appreciated that the split ring 20 lends itself to ready assembly of the parts.

In addition to the elements referred to, my novel wrench comprises a longitudinally adjustable washer and nut retainer 21, the element being so designated because of its adaptability of the position shown in Figures 1, 2 and 3, to retain a washer and nut in the member 12 and this in such manner 80 that there is no interference with the turning of the member 12 and the nut and washer about a common axis. The retaining member 21 is provided with an enlarged bifurcated end portion 22, and it is also provided with a shank, the said shank being guided and movable rectilinearly in the aperture 4 in the handle portion 1, and being provided with a rear hooked shaped portion 22, the bight of which is disposed and movable in 85 the before mentioned slot 2 of the handle portion 1. It will be noticed by reference to Figure 2 that the handle portion 1 is provided in one side with an indenture or depression 23, and that the bill of the hook 22 is provided with a projection 23^x designed to 90 be sprung into and out of the depression 23.

It will be apparent from the foregoing that when the retaining element 21 is moved to the position shown to retain a washer and nut in the member 12, the springing of the projection 23^x into the depression 23 will serve to hold the retainer 21 against casual movement. When however a little stress is applied to the end of the hook bill, the 105 110

member 21 may be easily retracted so as to release the washer and nut and leave the member 12 free to be disengaged from the said washer and nut.

5 In the use of my novel wrench for the installation of new bands in Ford automobiles, the washer and nut are placed within the turnable member 12, and the retainer 21 is moved to the position illustrated, whereupon casual displacement of the washer and nut from the member 12 will be precluded. With the washer and nut disposed as stated, my novel wrench is used merely to start a nut on a shaft, and after the nut with the washer before it is started on the shaft, the retainer 21 is retracted, the member 12 is disengaged from the washer and nut, and then the ratchet portion of my novel wrench is used to tighten the nut.

20 Notwithstanding the practical advantages of my novel wrench, it will be appreciated from the foregoing that the wrench is simple and inexpensive in construction, is susceptible of being readily manipulated, and in general is well adapted to withstand the usage to which wrenches of corresponding types are ordinarily subjected.

I have explicitly described the construction and relative arrangement of the parts 30 embraced in the present and preferred embodiment of my invention in order to impart a full, clear, and exact understanding of the said embodiment.

I do not desire, however, to be understood 35 as limiting myself to the precise structure disclosed, my invention being defined by my

appended claim within the scope of which modifications may be made without departure from my invention.

Having thus described the invention, what I claim is:—

In a wrench and in combination, a handle portion having a longitudinal slot, and a depression in one side adjacent to said slot and also having at an intermediate point a lateral offset and a longitudinal aperture therein, and further having an annulus with an inwardly directed flange, a turnable nut receiving member having a flange disposed within the annulus of the handle portion and opposed to the flange of said annulus and also having a roughened portion disposed laterally to the plane of the handle portion and a circumferential flange spaced from the flange of the annulus, a split ring 55 surrounding the turnable member and interposed between the flange thereof and the flange on the annulus, and a longitudinally movable nut retainer having a bifurcated portion movable into and out of coincidence with the turnable member, and also having a shank disposed and movable in the aperture in the offset of the handle portion and further having at its rear end a hook, the bight of which is disposed in the slot 60 of the handle portion and the bill of which is provided with a projection adapted to be sprung into and out of the depression in the handle portion.

In testimony whereof I affix my signature.

GILBERT H. SPECKMAN.
